GATE

Charles N. Dilatush, Memphis, Tenn.

Application August 28, 1939, Serial No. 292,281

4 Claims. (Cl. 39—60)

This invention relates to gates, and particularly to means for opening the gate on the approach of a vehicle thereto and the subsequent closing of the gate after the passage of the vehicle.

The invention further relates to means in such a structure for coordinating the parts so that the actuating part of the mechanism may operate in advance of the actual opening part of the mechanism, and to means adjusting the counter-balancing of the gate as to allow faster or slower closing.

The objects of the invention are:

To provide a gate which is simple in structure and may be economically built; which will readily open and close in response to the passage of a vehicle; which has opening and closing means controlled by the vehicle passage; which has provision for adjusting the counter-balancing weights, and in which the shock incident to passage of the vehicle is absorbed so that neither jar to the vehicle nor undue strain on the gate or parts may be exerted.

The means by which the foregoing and other objects are accomplished and the manner of their accomplishment will readily be understood from the following specification on reference to the accompanying drawings, in which:

Fig. 1 is a perspective view showing the relative positioning of the gate and the actuating mechanisms therefor.

Fig. 2 is a side elevation of the gate taken on the line II—II of Fig. 3; and

Fig. 3 an end elevation of the gate and side elevation of the actuating mechanism.

Fig. 4 is a side elevation of the hinged end of the gate showing a modified way of attaching the raising cable; the gate as in the preceding views being closed; and

Fig. 5 a corresponding end elevation; and

Fig. 6 is a side elevation corresponding to Fig. 4 showing the gate open, one of the supporting parts being omitted in both Figs. 4 and 6.

Referring now to the drawings in which the various parts are indicated by numerals:

The gate may be of any desired form or structure, and for purposes of illustration, is shown to comprise a top rail 10, bottom rail 11, and end rails 12 and 13, forming a frame work supporting a latticed wire structure 14. The top rail 10 has an extension 15 beyond the end rail 13, and the bottom rail 11 has an arcuately curved extension 16, likewise beyond the end rail 13, this latter extension curving upwardly and being joined to the top rail extension 15.

The rail 13, substantially midway of its height, carries a hub 17 which is pivotally mounted on a horizontal pin 18 disposed at right angles to the gate structure and carried by posts 19 which are firmly set in the ground. The hub member 17 may be a pipe fitting of the cross type and the end rail 13 in two sections screwed thereinto, the pin 18 passing through the branches of the cross at right angles to the rail connecting branches. Preferably an intermediate member 10 20 extends horizontally and rearwardly from a connection with the hub 17 to the extension 16 of the bottom rail.

Carried by the rearward extension 15, 16 of the gate is a counter-balance weight structure, this 15 structure preferably comprising an arcuate channelway 21 disposed along the arcuate extension 16 and being rigidly secured thereto. This channelway is adapted to receive weights 22, such number of these weights being used as is necessary to effect a counterbalance of the weight of the gate structure, it being obvious from the foregoing and subsequent descriptions that the weight of the gate must somewhat over-balance the weight of this counter-balance in order that 25 the gate may close by gravity.

To provide for adjustment of the counter-balance weight structure, abutment anchors 23 are provided, which anchors permit the placing or removal of the weights 22—A, 22—B, or the 30 shifting of these weights as desired above the weight 22—C, the channel 21 being extended upward for that purpose. The weights 22 below the bar 20 will ordinarily remain in the channelway without attachment, but preferably some 35 retaining means, as the bar 24, is used to prevent displacement of any weights above the bar 20.

An arcuate drum 30 is secured to the end rail 13, above and below the center pin 18, and is also secured to the bar 20 rearwardly of the pin. 40 Passing around the drum are cables 31, 32, each of these cables preferably having a spring section, only one of which, 31—A, is shown, through which spring sections attachment of the ends of the cables is made to the drum as by rivets or 45 bolts 33 near the upper portion thereof. The two cables 31, 32 extend downwardly and forwardly to and over pulleys 34, 35 respectively, and thence in opposite directions to the actuating mechanisms. Interposed in each of the cables between the pulleys 34 and 35 and the actuating mechanisms are tension springs 36, 37 respectively. From these spring sections the cables extend 50 respectively to and over pulleys 38, 39; and 40, 41 respectively to trip levers 42, 43. The lower ends 55

of these levers, as the lever 43 (Fig. 1), are provided with hub members 44 which are turnably mounted on horizontal bar portions 45 forming part of actuating members, generally designated by the numerals 46 and 47.

Each actuating member comprises this horizontal portion carried in bearings 48, 49, and having at its inner end an upwardly turned portion 50 which is reversely bent to form a horizontal arm 51, adapted to operably contact the lever 43. At its outer end the horizontal portion 45 has an upwardly turned and inverted shallow U shaped continuation 52, the bottom of the U being greatly elongated as compared with the length of the legs. Preferably the outer leg of the U has an outwardly turned portion 53 which is journaled in a bearing 54, the bearings 48 and 54 being suitably carried and aligned by a base 55. Positioned adjacent the base 55, is a frame work comprising upright posts 60, 61 and a horizontally disposed member 62, the pulley 41 being mounted adjacent the lower end of the post 60 and the pulley 41 adjacent the top of the post 60. 63 is a tension spring acting to pull the lever 43 into vertical position, movement being stopped by a stop member 64 mounted on the horizontal member 62. 65 is a spring which is secured to the member 62 and to the arm 50 of the actuating member and adapted to restore this member to upright position.

66 is a latch mounted as on a pivot pin 67 carried by the post 61, which latch has a notched lower end 68 adapted to engage with and retain the swinging end of the trip lever 43 when same is depressed by action of the horizontal arm 51, the latch being held in engaging position by a tension spring 69. 70 is a stop limiting this movement. 71 is a similar latch for the lever 42.

A cable 75 extends from the arm 51 of the actuating member 46 to the latch 71, and a similar cable 76 from the arm 51 of the actuating member 47 to the latch 66.

The gate is intended to close, and is counterbalanced to allow closing by gravity. The free end of the gate, formed by the rail 12, when closed is disposed in a slotted post 80, shown in Fig. 1 as a channel-shaped post 80, as of wood, and in Fig. 2 as a channel-shaped post 80—A.

It is sometimes found that when the gate is raised (Fig. 6) the relaxed tension of the spring of the cables 31, or 32 as the case may be, acting on the short radius of the drum is insufficient to hold the gate steady. In Figs. 4 to 6 inclusive the cables, 31 and 32, after passing partially around the drum 30, are secured to a ring 85 which is slidably mounted on a rod 86, having one end secured to the drum and its opposite end as through a block 87 to the channel 21. Spring sections 31—A may be interposed, as before, between the cable and the attaching means, the ring 85.

In constructing the device the posts 19 are set up adjacent the gateway opening and the gate mounted on the pin 18 supported by the posts. 65 The actuating members 46 and 47 are positioned in the edge of the roadway leading to and from the gate and at a desired distance from the gate in opposite directions, the distances, however, not necessarily being equal. In placing the actuating members, the U members 52 are obviously in the line of travel of one set of wheels of vehicles which will approach or leave the gate. The two frame works related respectively to the actuating members 46 and 47 are set up, and the cables 75 31 and 32 with their interposed springs 36 and

37 are connected from the gate drum 30 in opposite directions to the trip levers 42 and 43 respectively. The latch cables 75 and 76 are also connected from the arms 51 of the actuating members to the latches 71 and 66 respectively. 5

In operation, as the vehicle approaches the gate, as from the right, in Figs. 1 or 3, the wheel strikes the U portion 52 of the actuating member 47 forcing this U portion to the left, and through the arm 51 similarly moves the trip lever 42, the end of the lever moving in the arcuate pathway A downward into engagement with the notch at the lower end of the latch 71 and being held by the latch in such position, the U portion 52 after passage of the wheels being returned to upright position by the spring 65. Movement of the trip lever 42 correspondingly moves the cable 31, this movement being initially absorbed by the spring 36 and by such spring gradually transferred through the continuation of the cable 31 and the spring 31A to the drum 30, starting and completing the raising of the gate and holding this gate in raised position so long as the trip lever 42 is held by the latch 71. After the vehicle passes the gate it strikes the U portion 52 of the actuating member 46 forcing that U also to the left, and through the arm 51 and the cable 75 therefrom to the latch 71, disengages this latch and allows the trip lever 42 to be returned by the spring 63 to its initial position against the stop member 64, releasing the tension on the cable 31 and allowing the gate to descend by gravity to closed position.

In the form of attachment shown in Figs. 4 to 6, the ring 85 slides down the rod 86 when the gate is raised increasing both the length of actuating arm, the distance from the pin 18, and the direct tension on the cables 31, or 32. 35

I claim:

1. The combination of a pair of supporting posts, a gate having one end arranged between and extending rearwardly beyond said posts, a pin transverse to said gate carried by said posts and pivotally supporting said gate, and operating means, including an arcuate drum carried by said end, a pair of cables secured to said drum adjacent the top thereof and extending rearwardly, downwardly, and forwardly therebeyond, said cables respectively extending thence in opposite directions to actuating mechanisms; said actuating mechanisms including a member having an inverted U shaped portion disposed substantially upright in, and transverse to the wheelway of vehicles passing through said gate, means oscillatably supporting said member for depression of said U in opposite directions by vehicles approaching and leaving said gate, means tending to hold said U in upright position, an upright lever having its lower end pivotally mounted in adjacency to said U, said lever being in the path of movement of a portion of said member and depressible responsive to said approach movement, a latch for retaining said lever in depressed position, said drum cables being connected respectively to said levers for operative movement responsive to respective depression thereof; and cables each operably connecting the said latch of one said actuating mechanism to an oscillating member post of the other said actuating mechanism for disengaging movement of said latch, by vehicle leaving movement.

2. The combination of a pair of supporting posts, a gate having one end arranged between and extending rearwardly beyond said posts, a pin transverse to said gate carried by said posts 75

and pivotally supporting said gate, and operating means, including an arcuate drum carried by said end, a pair of cables secured to said drum adjacent the top thereof and extending rearwardly, therearound, said cables respectively extending thence in opposite directions to actuating mechanisms and each including a tension spring section, said actuating mechanisms including a member having an inverted U shaped portion disposed substantially upright in, and transverse to the wheelway of vehicles passing through said gate, means oscillatably supporting said member for depression of said U in opposite directions by vehicles approaching and leaving said gate, means tending to hold said U in upright position, an upright lever having its lower end pivotally mounted in adjacency to said U, said lever being in the path of movement of a portion of said member and depressible responsive to said approach movement, a latch for retaining said lever in depressed position, means resiliently urging said latch into engaging position, said drum cables being connected respectively to said levers for operative movement responsive to respective depression thereof; and cables operably connecting the said latch of one said actuating mechanism to said member portion of the other said actuating mechanism for disengaging movement of said latch, by vehicle leaving movement.

3. The combination of a pair of supporting posts, a gate having one end arranged between and extending rearwardly beyond said posts, a counter-balance carried by said end, a pin transverse to said gate carried by said posts and pivotally supporting said gate, and operating means, including an arcuate drum carried by said end, a pair of cables secured to said drum adjacent the top thereof and extending rearwardly therearound, said cables respectively extending thence in opposite directions to actuating mechanisms and each including a tension spring section, said actuating mechanisms being disposed in a wheelway of vehicles passing through said gate, and each including a number oscillatable in opposite directions by respective approach of a vehicle to, and departure of said vehicle from the gate, means for restoring said member to initial posi-

tion after either said oscillation, an oscillatable trip lever in the path of approach-responsive movement of said member, and operably movable by said member, a latch adapted to detainingly engage said lever, and means mounting said member, said restoring means, said lever and said latch; said cables being respectively each connected to a said lever for operative response to said movement thereof, and a second pair of cables respectively each having one end operatively connected to the said member of one said actuating mechanism and the other end connected to the latch of the other said mechanism for release actuation of said latch on departure-responsive movement of said member.

4. The combination of a pair of supporting posts, a gate having one end arranged between and extending rearwardly beyond said posts, means carried by said posts and pivotally supporting said gate, an arcuate drum carried by said end, a pair of cables secured to said drum adjacent the top thereof and extending rearwardly therearound, said cables respectively extending thence in opposite directions to actuating mechanisms and each including a tension spring section; said actuating mechanisms being disposed in a wheelway of vehicles passing through said gate, and each including a member oscillatable in opposite directions by respective approach of a vehicle to, and departure of said vehicle from the gate, means for restoring said member to initial position after either said oscillation, an oscillatable trip lever in the path of approach-responsive movement of said member, and operably movable by said member, a latch adapted to detainingly engage said lever, means resiliently holding said latch in engaging position, and means mounting said member, said restoring means, said lever and said latch; and a second pair of cables respectively each having one end operatively connected to the said member of one said actuating mechanism and the other end connected to the latch of the other said mechanism for release actuation of said latch on departure-responsive movement of said member.

CHARLES N. DILATUSH.
